UNITED STATES PATENT OFFICE

DOUGLAS A. WILSON, OF PEORIA, ILLINOIS, ASSIGNOR TO ROWE MANUFACTURING COMPANY, OF GALESBURG, ILLINOIS, A CORPORATION OF ILLINOIS

OVERHEAD DOOR CONSTRUCTION

Application filed August 3, 1929. Serial No. 383,301.

This invention relates generally to overhead door constructions and particularly to such constructions which are especially adaptable for use in connection with garage doors and the like.

Many of the smaller type garages now employed for housing individual cars present a comparatively small space between the upper edge of the door opening and the ceiling, and therefore render impossible the installation of conventional types of overhead garage door constructions. In some instances this overhead space is not more than six or seven inches and obviously in order to effect the 10 positioning of a group of door panels from the vertical door closing position to a horizontal position within the overhead space it requires that certain of the operating mechanisms be particularly designed for installation within said restricted space. It is one of the primary objects of my present invention to provide a device of improved practical design which will readily lend itself for use in connection with garages and the like 20 which present the above mentioned restricted overhead space.

In accordance with the above mentioned object I propose to provide a door construction comprising a plurality of connected door panels in which the uppermost panel may be quickly swung rearwardly away from the door jamb the instant that an upward force is imparted thereto, whereby to reduce to a minimum the degree of upward travel of the uppermost portion of said door panel and thus require a comparatively small overhead space to render possible the installation of the device.

A still further object of my invention is to 40 so arrange the flexible cables or chains and pulleys for guiding same that they will occupy a position below the uppermost plane of the panel supporting guide rails and thereby require the space above the guide rails to be 45 used only for receiving the door panels. By such a construction my device is capable of being installed within garages having a minimum ceiling or overhead space.

Still another object of this invention is to 50 provide an improved practical means of sim-

ple and durable construction which will serve to automatically cause the uppermost door panel to be tightly urged against the door jamb when said panels occupy their vertical door closing position, said means being also arranged to permit the free rearward swinging of the uppermost door panel the instant that an upward force is imparted thereto.

My invention also contemplates the provision, in combination with the above mentioned door operating mechanisms, of a deflector which is adapted to be engaged by the upper edge of the uppermost panel and which serves to cause said panel to be positively swung rearwardly.

It is also an object of my present invention to so position the lifting cables or chains as to reduce to a minimum the possibility of causing said elements to interfere with the free to and from movements of the door panels and to this end I propose to position said cables or chains to one side of the guide rails and also provide means for positively guiding said chains.

With the foregoing and other objects in view, which will appear in the following description, the invention resides in the novel combination and arrangement of parts and in the details of construction hereinafter described and claimed.

In the drawings:

Figure 1 is a rear elevational view of an overhead door construction which is representative of one embodiment of my invention, the same being shown in operative association with a garage, said view being taken substantially along the line 1-1 of Figure 4;

Figure 2 is an enlarged detailed view of a modified form of roller support for the lowermost door panel;

Figure 3 is a side elevational view thereof as viewed from the left of Figure 2, the lifting chain and roller being removed for the purpose of more clearly disclosing parts otherwise hidden;

Figure 4 is a vertical transverse sectional view of the overhead door construction, said view being taken substantially along the line 4-4 of Figure 1;

Figure 5 is a view similar to Figure 4 disclosing the door panels in their overhead position;

Figure 6 is a fragmentary perspective view disclosing in detail the guide rail and spring support carried thereby, said view being taken substantially along the line 6—6 of Figure 4;

Figure 7 is a fragmentary detailed view disclosing a counterbalancing means of modified construction in association with a lifting spring;

Figure 8 is an enlarged detailed side elevational view of the guide rail construction as viewed along the line 8—8 of Figure 1, the door panels being disclosed in their uppermost or horizontally disposed position;

Figure 9 is a view similar to Figure 7 disclosing the lowermost door panel in an intermediate position;

Figure 10 is a detailed perspective view of the corner of the lowermost door panel, the lifting chain and roller being detached in order to more clearly disclose the structural characteristics of the chain supporting bracket;

Figure 11 is a fragmentary transverse sectional view of the vertical section of the guide rail and support therefor taken substantially along the line 11—11 of Figure 8;

Figure 12 is a fragmentary plan view of one of the guide rails and pulleys associated therewith;

Figure 13 is a front elevational view of the structure shown in Figure 12;

Figure 14 is an enlarged fragmentary sectional view of the door closing lever and the lever actuating spring associated therewith taken substantially along the line 14—14 of Figure 13; and

Figure 15 is an enlarged fragmentary elevational view of the hinge structure at the lower end of the uppermost panel, said view being taken from the left of Figure 13.

Referring now to the drawings more in detail wherein like numerals have been employed to designate similar parts throughout the various figures, it will be observed that one embodiment of my invention contemplates the provision of a pair of guide rails 20 which are adapted to be positioned at opposite sides within a garage indicated generally by the numeral 22. The extremity of the upper horizontally disposed portion of the guide rails is secured in any suitable manner as by means of a depending support 24 and the front or vertically disposed sections of said guide rails are secured to the door jambs 26 by means of supports 28, (see Figures 8 and 11). The outer portions of the supports 28 are secured to the guide rails as by means of bolts 30 while the inner U-shaped sections 32 of the supports are suitably secured to the door jamb 26. The guide rails are provided with a curved section 34 which is adapted

to accommodate rollers in the manner hereinafter to be described.

The door proper comprises a plurality of door sections 36, 38, 40 and 42. The panels 36 and 38 are hinged together by means of a stub shaft 44, Figure 15, and a pair of co-operating hinge elements 46 and 48 through which the pin 44 extends. Surrounding the pin 44 and extending between the projecting portions of the hinge members 46 and 48 is a sleeve 50 which forms the bearing around which said elements 46 and 48 pivot. The outer extremity of each of the pins 44 carries a roller 52 which is adapted to be guided within its companion guide rail 20. Hinge elements similar to the elements 46 and 48 connect the panels 38 and 40 and a roller 54 carried thereby is guided within the rail 20. Likewise the panels 40 and 42 are hinged together and the pin passing through said hinge supports a roller 56 at its outer extremity. Secured at each corner to the inside surface of the lowermost panel 42, Figure 1, is a plate 58 which carries a pin 60 and this pin 60 supports a roller 62 which is guided within the rail 20.

In this connection it is to be observed that when the door panels occupy their vertical position as shown in Figures 1 and 4, the distance between the axis of the roller 52 and the inner surface of the door panels is greater than the distance between the axis of the roller 54 and said surface. Likewise the distance between the axis of the roller 56 and said surface is greater than the distance between the axis of the roller 58 and said surface and similarly the distance between the axis of the roller 62 and the inner door surface is less than the distance between the axis 56 and the door surface. The vertical sections of the guide rails are spaced slightly closer to the inner surface of the door panels at their lower extremities than they are at their upper extremities and hence the above mentioned distances are arranged accordingly so as to effect the clamping of the panels against the door jambs when said panels occupy their door closing position as shown in Figures 1 and 4.

Straddling the hinge elements 46 and 48 connected between each end of the uppermost door panel 36 and the next adjacent panel 38 is a pair of straps 64 and 66, Figures 13 and 15. These straps are pivotally mounted at one extremity upon the pin 44 and clamped between the opposite extremities of said straps by means of suitable bolts 68, is a connecting member 70. The opposite extremity of this member 70 is connected by means of bolts 72 to a plate member 74 which forms a part of a carriage device indicated generally by the numeral 76.

This carriage device 76 includes the upper extremities of the connecting member 70 and interposed between these carriage devices is

a tie rod 78, Figures 1, 12 and 13. This tie rod 78 is secured to the upper portion of the connecting members 70 by means of suitable bolts 80. This carriage device 76 also includes rocker arms 82 pivotally mounted upon pins 83 extending through and secured at one extremity to the upper end of the connecting member 70 as clearly shown in Figure 14. One extremity of this rocker arm 82 is adjustable in length through the agency of a movable arm portion 84 which is provided with a pair of slots 86. Bolts 88 extend through these slots and enable the section 84 to be clamped in various positions of longitudinal adjustment. The opposite extremity of the rocker arm 82 is adapted for engagement with a stop pin 90 which is carried by a side plate 92, Figure 13. The engagement of the rocker arm with this stop pin 90 causes said arm to be swung in a clockwise direction as viewed in Figure 13 so as to carry the outer extremity of the adjustable arm section 84 into engagement with the rear side of the upper door panel 36. A coiled spring 94 encircles the portion of the pin 83 extending outwardly from the rocker arm 82, one extremity 96 of this spring being secured to the rocker arm as clearly shown in Figure 14 and the other extremity 98 secured to a housing 100 which is mounted upon and secured to the pin 83 as by means of a cotter-pin 102. It will thus be apparent that by having the extremity of the pin 83 secured against rotation within the upper end of the connecting member 70 and the plate 74, this coiled spring 94 will serve to constantly urge the rocker arm 82 in a counter-clockwise direction. The outer extremity of the plate 74 carries a roller 104 which is adapted to travel along the outer surface 106 of the guide rail 20, Figures 6, 12 and 13.

The operation of the carriage device 76 just described will be more readily understood by observing the movements of the carriage elements when the door panels are elevated. Suppose for example that the door panels are urged upwardly from the door closing position shown in Figure 13. This will immediately cause the carriage 76 to be elevated and as said carriage is elevated, the rocker arm is rotated in a counter-clockwise direction, thereby moving the adjustable arm section 84 rearwardly to permit the uppermost door panel 36 to be quickly swung rearwardly. The coiled spring 94 in this instance serves to positively effect the counter-clockwise movement of the rocker arm and rearwardly extending deflectors 108 are adapted to be engaged by the upper edge of the door panel 36 and thereby positively urge said panel rearwardly. As the door panel 36 swings rearwardly it passes between the plates 74 and when the carriage occupies the dotted position shown in Figure 13, said panel will have been swung to a position where it will

rest upon the outer surface of the coiled spring housing 100. During this movement the rocker arm is swung through an angle of substantially 90 degrees thereby permitting the door panel to experience a rapid rearward swinging movement. This rapid rearward swinging movement of the door panel enables said panel to be moved from its substantially vertical position with a minimum degree of elevation of the upper edge of the panel. In other words, the amount of space which is required above the upper plane of the horizontal portions of the guide rails 20 for receiving the door panel is reduced to a minimum. When the door panels have been moved to their limiting overhead position shown in Figure 5, the uppermost panel will be inclined downwardly and will rest upon the housings 100 and the lowermost panel will also be inclined downwardly to a slight degree. It will thus be seen that the carriage device 76 operates independently of any of the door panels in the sense that the rocker arms and rollers forming a part thereof are not positively connected to the upper panel but serve as an effective independent means for controlling the proper functioning of said upper panel. As the door panels are moved from their overhead position shown in Figure 6 to their vertical door closing position, the rocker arm 82 is eventually moved into engagement with the stop pin 90. Continued movement of the door panels causes the rocker arm to be swung in a clockwise direction against the action of the coiled spring 94, thereby causing the adjustable arm sections 84 to be swung into engagement with the panel 36 so as to effect the positive closing of said panel against the door jambs.

I will now describe my improved means for effecting the lifting of the door panels. This means includes a flexible member or chain 110 which is associated with each of the guide rails 20. One extremity of each of these lifting chains 110 is secured to a bracket 112 carried at the lower extremity of the lowermost door panel 42. This bracket extends outwardly from the door panel as clearly shown in Figure 10 and is provided with apertures 114 through which a bolt may be inserted for retaining the extremity of the chain 110 in position. When the door panels occupy their closing vertical position, these chains 110 extend upwardly from their respective brackets and pass through the U-shaped section 32 of the supports 28 and at the point where the guide rail 20 begins to curve rearwardly I provide a pulley 116 over which the chain 110 passes, Figure 13. From this point the chain extends to a second pulley 118 carried by the plate 92 and then passes over a pulley 120 which is carried at the extremity of a heavy duty lifting spring 122. From the pulley 120 the chain passes forwardly to the plate 92 where it is suitably

anchored as by means of a hook 124. This heavy duty spring 122 extends to one side and beneath the rail 20 and is secured at its opposite extremity to a suitable connecting member or rod 126. This rod 126 extends through a second spring 128 which is weaker than the heavy duty spring 122. The outer extremity of the rod 126 is threaded to receive a nut 130 which bears against a washer 10 or other device which bears against the outer end of the spring 128. To support the heavy duty spring 122 I provide a U-shaped support 132, Figures 4, 5 and 6 which depends from the horizontal section of the guide rail 15. 20. When the door panels occupy their closing or vertical position, the heavy duty counter-balancing spring will be in tension and the lower spring 128 will be placed in compression and the weight of the door panels 25 will be sufficient to overcome the tendency of said springs to cause said panels to be raised.

It is believed that the functional characteristics of my improved lifting and counter-balancing means will be more readily appreciated if the operation thereof is described in connection with the opening and closing of the door panels. Thus, suppose that a lifting force is applied to the door panels as for example by pulling upwardly on a central handle 134 positioned at the central lower portion of the door panel 42, Figure 1. As the panels are raised, the tension in the spring 122 causes the slack in the chain to be taken up and when the lowermost door panel 42 reaches the position shown in Figure 9, the chain 110 leaves the pulley 116. When said panel reaches the limit of its upward movement or in other words, occupies the position shown in Figure 8, the chain will have been doubled back over a roller 136 which is secured to the outer surface of the guide rail 20. The engagement of the chain with this roller serves, in co-operation with the action of the counter-balancing springs, to give a cushioning effect as the door panels reach their overhead position. In other words, as the chain 110 is wrapped around the roller 136, the rearward sliding movement of the door panels is not abruptly retarded because 50 said chain is connected to the counter-balancing springs 122 and 128 through the agency of the pulley 120. That is to say, as the chain is moved into engagement with the roller 136, there is a certain amount of pull exerted upon 55 the springs as the door slides rearwardly, with the result that a cushioning effect is experienced by the door as its rearward movement is arrested. In this manner sudden jarring and slamming of the door panels is 60 positively avoided. By having the chains positioned as described, namely externally of the guide rails, I am able to obtain very free or smooth running operation thereof.

In this connection attention is directed to 65 the fact that none of the elements constituting

the above described lifting and counter-balancing means are positioned above the upper plane of the guide rail. In fact, all of said devices are positioned below said plane and thereby avoid the necessity of using the overhead space in the garage to accommodate such elements. This is decidedly advantageous in instances where head room is limited as for example in smaller sizes of garages where the distance between the upper portion of the door opening and the ceiling or cross beams is very limited. The pulleys over which the chain travels provide very effective guiding means and insure positive and free running action. Attention is also directed to the fact that the 70 spring 128 and the rod 126 connected thereto provide a very convenient shifting means for causing a greater or lesser tension to be thrown upon the main lifting spring 122. The advantage of such a shifting means will 75 be apparent when it is understood that often-times the door panels are shifted upwardly with considerable force and upon reaching the limit of their upward overhead position there is a tendency for a rebound. Experience has shown that in some instances when the door panels are moved to their overhead or horizontal position, there is a tendency for the heavy duty spring to oscillate unless 80 some means for counter-acting this tendency 85 is provided. This oscillating effect results from the sudden contraction of the spring as the door panels are moved to their overhead position. This sudden contraction obviously tends to cause the repeated expansion or contraction or in other words, oscillation of the 90 spring. Under such circumstances the lighter spring 128 serves to counter-act the tendency for the spring 122 to oscillate. This will 95 be clear from Figures 4 and 5 of the drawings. In Figure 4 the heavy duty spring 122 is expanded and the lighter spring 128 is contracted and thereby counter-acts the tension 100 in the spring 122. However, when the spring 122 has been carried to the position shown in 105 Figure 5, the spring 128 assumes its normal expanded position and thereby counter-acts any shifting of the spring 122 to the right. In this manner the spring 128 serves to counter-act any oscillating movements of the 110 spring 122. In Figure 5 the spring 122 is shown as being completely contracted and the tension in the spring 128 is sufficient to exert 115 a force on the spring 122 and the chain 110 to prevent said elements from sagging. Obviously, other shifting means might be employed for causing a greater or less tension to be placed upon the main lifting spring without departing from the spirit and scope of the 120 present invention. The types of heavy duty 125 springs which are employed in connection with garage doors of the type described, have a tendency to oscillate for a considerable period after the door has been swung upwardly, and as above described, my improved 130

compensating or shifting means 128 serves to positively avoid this difficulty. In Figure 7 I have disclosed a modified means in the form of a weight 138 which is connected to the extremity of the main or heavy duty spring 122 by means of a flexible cable 140 which passes over a pulley 142. I prefer, however, to employ the spring 128 in most instances.

In Figures 2 and 3 I have disclosed a modified arrangement for supporting the pin 60 and the roller 62 at the lower portion of the door panel 42. It will be noted that in this modified arrangement I support the pin 60 in a bracket 144 which is pivotally mounted at its upper end between a pair of ears 146 projecting outwardly from the plate 58. In instances where a relatively narrow bracket such as the bracket 112, Figure 10, is employed, it may not be necessary to have the shaft 60 mounted in the manner shown in Figures 2 and 3. However, where it is necessary to have a heavier type of bracket as for example a bracket which is nearly as thick as the door panel itself, it would be necessary 25 to have relative movement between the roller and the door panel. This will be apparent when it is understood that the surface of the bracket 112, Figure 10, which I have indicated by the numeral 146', must slide along 30 the upper surface 106 of the guide rail when the door panels are horizontally positioned. Hence, when the panel 42 reaches this upper position, the distance between the surface 146' and the axis of the roller 62 must necessarily 35 be increased.

From the foregoing description it will be understood that my invention contemplates the provision of an overhead door construction which is of simple and durable construction and which readily lends itself for use in connection with door openings for garages and the like. One of its outstanding advantages resides in the fact that the uppermost door panel may be quickly swung rearwardly 45 in such a manner as to reduce to a minimum the distance through which the upper edge of said panel must be elevated. In this manner only a very small portion of the space above the rails need be employed to enable 50 the upper edge of the panel 36 to be moved from a vertical to a horizontal position. To further expedite the installation of my improved door operating mechanism I have positioned all of the lifting devices such as 55 the lifting chain, pulleys, counter-balancing springs and the like below the upper plane of the guide rails. In this manner I have eliminated the necessity of employing overhead space to accommodate these elements. In 60 fact, when the door panels occupy their normal door closing position as shown in Figure 4, nothing projects into the space above the guide rails except the deflecting element 108 which is positioned immediately above the 65 door jamb. The independently operable car-

riage mechanism for controlling the operation of the upper door panel 36 provides an effective means for permitting the upper panel to be quickly swung rearwardly and also serves to positively effect the closing of said upper door panel. It will be observed that when the adjustable portion of the rocker arm is swung rearwardly away from the upper panel, said panel freely rests upon the spring housing and is not in any way positively connected to the carriage device. In this manner the upper door panel may quickly be removed with considerable ease for purposes of repair or replacement, it being only necessary to disengage the panel from association with the hinge pins 44. The rollers 52, 54, 56 and 62 are so positioned with respect to the inner surfaces of the door panels that they will cause said panels to be tightly forced against the door jamb. Attention is directed to the position occupied by the roller 104 carried by the plate 74 when the door panels are in their closing position as shown in Figure 4. In this position the axis of the roller 104 is positioned at a distance from the inner surface of the door panels which is less than the distance between the axis of the rollers 52, 54, 56 and 62 and said surface. This results from having the roller 104 movable along the outer surface 106 of the guide rail and enables the rocker arm to be forced tightly against the door panel 36. The counter-balancing means as above described, serves to effectively avoid any to-and-fro movement of the door panels after they have once been moved to their uppermost positions. Said counter-balancing means also operates to maintain the position of the panels during their partially closed setting, that is, said counter-balancing means will maintain the panels in any position of adjustment. The adjustable feature of the rocker arm enables said arm to be adjusted in accordance with the particular needs incident to its use. The carriage or panel controlling device is of rigid construction and serves as a very effective means for controlling the positioning of the uppermost panel.

The arrangement of the counter-balancing springs 122 and the take-up means associated therewith, such as the lighter duty spring 128 shown in Figures 4 and 5 and the weight 138 shown in Figure 7, is being covered in a separate divisional application filed December 26, 1929, Serial No. 416,498.

Having thus described my invention, what I claim as new and desire to secure by Letters Patent is:

1. In an overhead door construction of the class described, a plurality of hingedly connected shiftable door panels, guiding means to direct the movement of said panels between closed and opened overhead positions, and lifting means comprising a flexible lifting

- element operatively connected with said panels and positioned along the outer side of said panel guiding means, and means for directing the travel of said element, all of the parts constituting said lifting means being positioned below the upper plane of said door guiding means, whereby to reduce to a minimum the overhead space necessary for installation.
2. In combination with a door opening of a garage or the like, an overhead door construction comprising a plurality of hingedly connected shiftable door panels for traversing said door opening, guiding means to direct the movement of said panels between closed and opened overhead positions, the upper portion of said guiding means being positioned above the uppermost plane of the door opening, and lifting means for said panels including a flexible shifting element and guiding means therefor and positioned along the outer side of the panel guiding means, said lifting means being positioned below the upper plane of said door guiding means.
3. In an overhead door construction of the class described, a plurality of hingedly connected shiftable door panels, guiding means to direct the movement of said panels between closed and opened overhead positions, and lifting means including a flexible lifting element, guiding means therefor, and counter-balancing means, all of the constituent parts of said lifting means being positioned below the upper plane of said door guiding means, whereby to reduce the overhead space necessary for installation.
4. In combination with the door opening of a garage or the like, an overhead door construction including guide rails having substantially vertical sections adjacent the door jambs and a curved section connecting the vertical section with a substantially horizontal section, a plurality of hingedly connected door panels which are adapted to be guided by and moved along said rails, a flexible lifting element connected at one extremity to the lowermost door panel, the other extremity thereof being secured in a fixed position, pulleys for guiding said flexible element, and a counter-balancing means connected with said flexible element, said flexible element, pulleys and counter-balancing means being positioned below the upper plane of the horizontal section of the guide rails, thereby effecting a considerable reduction in the overhead space required for installation.
5. In an overhead door construction of the class described, a plurality of shiftable hingedly connected door panels, guiding means having vertically and horizontally disposed sections for directing the movement of said panels between a substantially vertical door closing position and a substantially horizontal overhead position, and lifting means therefor including a flexible lifting element operatively connected with the panels, and pulleys for directing the movement of said flexible element, one of said pulleys being positioned adjacent the upper end of the vertical section of said guiding means and below the upper plane of said guiding means and another adjacent the forward end of the horizontal section of said guiding means whereby to properly guide said flexible element in shifting between vertical and horizontal positions.
6. In an overhead door construction of the class described, a plurality of shiftable door panels, guiding means having vertically and horizontally disposed sections for directing the movement of said panels between a substantially vertical door closing position and a substantially horizontal overhead position, lifting means therefor including a flexible element operatively connected with the panels, pulleys for directing the movement of said flexible element, and means positioned adjacent said panel, guiding means in the path of the flexible element for engaging said element when the lower-most door section approaches its limiting overhead position.
7. In an overhead door construction of the class described, a plurality of shiftable door panels, guide rails having vertically and horizontally disposed sections for directing the movement of said panels, said vertically and horizontally disposed sections being connected by a curved section, lifting means including a flexible element operatively connected with the panels, guide rolls positioned at opposite extremities of the curved section of the rail for directing said flexible lifting element, and means positioned adjacent said rail intermediate said guide rollers for engaging the flexible lifting element as the lowermost door section approaches its limiting overhead position.
8. In an overhead door construction of the class described, a plurality of shiftable hingedly connected door panels, guide rails having vertically and horizontally disposed sections for directing the movement of said panels, a flexible lifting element operatively connected with said door panels, resilient counter-balancing means connected to said flexible lifting element and means positioned in the path of said flexible element which is adapted to be engaged after the doors reach their overhead position, thereby cooperating with said resilient counter-balancing means to give a cushioning effect in arresting the movement of said panels.
9. In an overhead door construction of the class described, a plurality of shiftable hingedly connected door panels, guide rails having vertical and horizontally disposed sections interconnected by a curved section for directing the movement of said panels between the door closing position and opened overhead position, a flexible lifting element

- secured at one extremity to the lower-most door panel and secured in a fixed position at its opposite extremity, rollers for guiding said flexible element, counter-balancing means operatively connected with said flexible element, and means positioned adjacent the curved section of said guide rail adapted to be engaged by said flexible element as the same is swung upward during the final movement of the door panels to their overhead position, said means cooperating with the counter-balancing means to effect a cushioning action in arresting the movement of said panels. 5
10. In an overhead door construction of the class described, a plurality of shiftable hingedly connected door panels, guide rails having vertically and horizontally disposed sections for directing the movement of said panels between a closed and open overhead position, lifting means including a flexible element, pulleys for directing the movement of said flexible element, and a bracket secured to the lower-most door panel and extending outwardly from the end thereof beyond the outer side of the guide rail, said bracket providing a mounting for one extremity of the flexible lifting element and serving to maintain a spaced relation between said flexible element and the side of the guide rail associated therewith. 15
11. In combination with the door opening of a garage or structure of like nature, an overhead door construction including guide rails having substantially vertical sections adjacent the door jambs, a curved section and a substantially horizontal upper section, a plurality of hingedly connected door panels which are adapted to be guided by and moved along said rails, and a panel controlling device associated with the upper-most panel and operable independently thereof, said device having means for engaging said upper panel to effect the closing thereof when said panel is moved to its closing position, and also independent means for supporting said upper panel when it assumes its overhead position. 20
12. In combination with a door opening of a garage or structure of like nature, an overhead door construction including guide rails having substantially vertical sections adjacent the door jambs, curved sections and substantially horizontal sections, a plurality of hingedly connected door panels which are adapted to be guided by and moved along said rails, and a panel controlling device positioned adjacent the upper-most panel, said device including a lever mechanism adapted to be moved into and out of engagement with respect to the upper panel, the movement toward the panel serving to clamp said panel against the door jamb and the movement away from the panel serving to permit the free swinging movement of the panel independently by the rail curvature as the door panels are moved upwardly. 25
13. In combination with a door opening of a garage or structure of like nature, an overhead door construction including guide rails having substantially vertical sections adjacent the door jambs, curved sections and substantially horizontal sections, a plurality of hingedly connected door panels which are adapted to be guided by and moved along said rails, and a panel controlling device positioned adjacent the uppermost panel, said device including a lever mechanism adapted to be moved into and out of engagement with respect to the upper panel, the movement toward the panel serving to clamp said panel against the door jamb and the movement away from the panel serving to permit the free swinging movement of the panel as the door panels are moved upwardly, and means for constantly urging said lever mechanism away from panel engaging relation. 30
14. In combination with the door opening of a garage or structure of like nature, an overhead door construction including guide rails having substantially vertical sections adjacent the door jambs, curved sections and substantially horizontal sections, a plurality of hingedly connected door panels which are adapted to be guided by and moved along said rails, a panel controlling device associated with the uppermost door panel, said device including a lever mechanism adapted to be swung into engagement with the upper-most panel to effect the closing thereof against the door jamb, and to be swung out of engagement with said panel when said panel is moved to the overhead position, independent means providing the sole support for the panel in its overhead position, and a fixed abutment adapted to be engaged by the lever mechanism to effect the panel closing actuation thereof. 35
15. In combination with a door opening of a garage or structure of like nature, an overhead door construction including guide rails having substantially vertical sections adjacent the door jambs, curved sections and substantially horizontal sections, a plurality of hingedly connected door panels which are adapted to be guided by and moved along said rails, and a panel controlling device associated with said rails, said device including a roller mounted upon said rail, a support for said roller, and a lever mechanism pivotally mounted upon said support, said lever mechanism adapted to be swung into engagement with the uppermost panel to effect the closing thereof against the door jamb and to be swung out of engagement with the panel when said panel is moved to the overhead position. 40
16. In combination with a door opening of a garage or structure of like nature, an overhead door construction including guide rails, 45

a plurality of hingedly connected door panels carried by said guide rails and adapted to be moved between closed and opened overhead positions, and a panel controlling device associated with said guide rail, said device having means for automatically engaging the uppermost door panel to effect the closing thereof and means for receiving said uppermost door panel as it is swung rearwardly upon the upward movement thereof, said means providing a rest for supporting said upper panel when said panel occupies its overhead position.

17. In combination with the door opening of a garage or structure of like nature, an overhead door construction including guide rails, a plurality of hingedly connected door panels which are adapted to be guided by and moved along said rails between closed and opened overhead positions, and a panel controlling device associated with said guide rail, said device including a lever mechanism for engaging the uppermost panel to effect the closing thereof against the door jamb, and a rest for receiving said uppermost panel as it is swung rearwardly away from the vertical position, said rest being designed to support the uppermost panel in its overhead position so as to permit said panel to be swung freely away from said rest, whereby to facilitate the detachment of said uppermost door panel.

18. In combination with a door opening of a garage or structure of like nature, an overhead door construction including guide rails, said rails having a substantially vertical section adjacent the door jamb, a curved section and a substantially horizontal section, a plurality of hingedly connected door panels which are adapted to be guided by and moved along said rails, a panel controlling device mounted on one of said rails, said device including means for effecting the closing of the uppermost panel and means for supporting said uppermost panel when said panel is moved to its overhead position, and means connecting said controlling device with the hinged structure between the uppermost and next adjacent door panel.

19. The combination with a door opening of a garage or structure of like nature, an overhead door construction including guide rails having a section positioned adjacent the vertical door jamb, a curved section and a substantially horizontal section, a plurality of hingedly connected door panels which are adapted to be guided by and moved along said rails, rollers carried by said door panels at points approximating their hinged connections, said rollers being guided in said rails, and a panel controlling device mounted upon one of said guide rails, said device including a roller movable along the guide rail, the distance between the axis of said roller and the inner surface of said door panels when in

closed position being less than the distance between the axis of the next adjacent panel supporting roll and said inner surface of the panels, whereby to effect the firm clamping of the upper panel against the door jamb.

20. In combination with the door opening of a garage or structure of like nature, an overhead door construction including guide rails, each of said rails including a section positioned adjacent the vertical door jamb, a curved section and a substantially horizontal section, a plurality of hingedly connected door panels slidably mounted within said rails, a deflecting means positioned above the door opening adapted to be engaged by the upper edge of the uppermost door panel, said deflector serving to effect the rearward swinging of said uppermost door panel, and means for receiving said uppermost door panel as it is swung rearwardly in response to the engagement of said panel with the deflector.

21. In combination with the door opening of a garage or structure of like nature, an overhead door construction including guide rails having substantially vertical sections adjacent each of the door jambs, curved sections and substantially horizontal sections, a plurality of hingedly connected door panels which are adapted to be guided by and moved along said rails, and a panel controlling device slidable along one of said guide rails, said device including a lever mechanism adapted to be swung into engagement with the uppermost panel to effect the closing thereof against the door jamb, said lever mechanism having means for adjusting the length thereof whereby the closing action of said lever mechanism may be adjustably controlled.

22. In combination with the door of a garage or structure of like nature, an overhead door construction including guide rails having a substantially vertical section adjacent each door jamb, curved sections and substantially horizontal sections, a plurality of hingedly connected door panels which are adapted to be guided by and moved along said rails, and a panel controlling device slidable upon said guide rails, said device including a lever mechanism adapted to be swung into engagement with said uppermost panel to effect the closing thereof and to be swung away from said panel to permit the rearward swinging thereof when said panel is moved toward its overhead position, said lever mechanism having a longitudinally adjustable lever arm for adjustably controlling the panel closing action of said arm.

23. In combination with the door opening of a garage or structure of like nature, an overhead door construction including guide rails having horizontally and vertically disposed sections, a plurality of door panels slidably within said guide rails, and flexible lifting elements secured at one extremity to the

lower-most door panel, said flexible elements being positioned externally to one side of the guide rails, whereby to avoid interference between the flexible elements and the guide rails.

5 24. In an overhead door construction of the class described, a plurality of hingedly connected shiftable door panels, guide rails for directing said panels from a substantially vertical position to a substantially horizontal overhead position, lifting means attached to an extension on the lower door panel, guiding means positioned at the lower corner of the lowermost door panel, said guiding means being movable along one of said guide rails, and a shiftable support for said guiding means, whereby said guiding means may be shifted laterally of the door panel to prevent said extension from binding on said guide means.

10 25. In an overhead door construction of the class described, a plurality of hingedly connected shiftable door panels, guide rails for directing said panels from a substantially vertical position to a substantially horizontal overhead position, lifting means attached to an extension on the lower door panel, guiding means positioned at the lower corner of the lowermost door panel, said guiding means being movable along one of said guide rails, and a pivotal mounting for said guiding means, whereby relative movement may be effected between said guiding means and the door panel with which it is associated, to prevent said extension from binding on said

15 25 guide means.

In witness whereof, I have hereunto subscribed my name.

DOUGLAS A. WILSON.
